UNITED STATES PATENT OFFICE.

LEON S. BRACH, OF EAST ORANGE, NEW JERSEY, ASSIGNOR TO L. S. BRACH MANUFACTURING CO., OF NEWARK, NEW JERSEY.

RADIO RESISTOR COUPLER UNIT.

Application filed July 21, 1925. Serial No. 45,029.

To all whom it may concern:

Be it known that I, LEON S. BRACH, a citizen of the United States, residing at East Orange, in the county of Essex, State of New Jersey, have invented certain new and useful Improvements in a Radio Resistor Coupler Unit, of which the following is a description, reference being had to the accompanying drawing and to the figures of reference marked thereon.

This invention relates to a unitary structure for use in connection with radio circuits, particularly, those used in a receiving set.

15 Numerous circuits are in use for the reception of radio waves and among these receiving circuits the resistance-coupler method may be found. In a resistance coupling circuit, the resistance units are usually associated in pairs in connection with a condenser and in order to simplify the wiring of a resistance coupling set, I have constructed a unitary device comprising a pair of resistance units with an associated condenser within a suitable casing with proper connections brought out to the terminals or binding posts on the exterior of the casing so that all that is required is the connecting of certain wires or bus-bars to the terminal posts of the unit; thus, the principal object 30 of my invention is at once apparent.

A further object of my invention is to provide a unit which is so constructed as to carry a suitable designation plate by which 35 the character of the unit may be readily ascertained.

Another object of my invention is to provide a unit as heretofore described which shall be small, compact and neat in design.

40 My invention will be best understood by reference to the attached drawing in which

Figure 1 is a plan view, approximately full size of the complete unit.

Figure 2 is a view of Fig. 1 from the bottom or reverse side from that shown in Fig. 1, but with the cover plate removed.

Figure 3 is a view similar to Fig. 2 but with the condenser removed.

Figure 4 is a section on the line 4—4 of Fig. 2.

Referring now to the drawing wherein like numbers refer to corresponding parts in the various views, 1 is a casing preferably of suitable molded material having a body 55 part 4 and flanges 2 on at least two sides,

or, ends of the casing. The flanges 2 are provided with a hole 3 for mounting the unit. The body part 4 of the casing is preferably slightly tapered, as indicated in Fig. 1, and is provided with a window 5. 60 The side walls of the casing around the windows 5 are beveled as indicated at 6. Within the interior of the body part of the casing 1 and over the window 5 is placed a strip 7 of transparent material such as celluloid behind which is placed a designation plate 8 on which may be stamped or printed the required data to identify the kind of resistor-coupler carried within the casing. 65 Preferably positioned behind the designation plate 8 is a backing strip 9. The parts 7, 8 and 9 may be held in position with respect to the window 5 in any satisfactory manner, but, I have chosen to hold these in place by bridging them with two resistance units 10 which are securely held within the casing by terminal screws or studs 11. These studs are identified on the outside of the casing 1, as shown in Fig. 1, by letters P for Plate, G for Grid, B for one side of 70 the battery and F for Filament.

75 Mounted within the casing 1 and directly over or behind the resistance units 10, is a condenser 12 which is provided with mounting lugs 13 and 14 that are engaged by one pair of the studs 11 as shown in Fig. 2 thereby bridging the condenser 12 directly across the ends of the resistance units 10. The bottom side of the casing is fitted with a cover 17 resting against the rim 15, the 80 cover plate being held in position by eyelets 16 as shown in Fig. 1. Since the resistance units 10 may be of different values, for, different conditions, it is essential to know what these values are on any given unit; 85 consequently, these values, together with the condenser value with any other indicia, is placed on the designation plate 8, and the information then appears through the window 5 so that the proper resistor-coupling 90 unit may be chosen when it is desired to connect them into a radio circuit.

95 From what has been said it will be seen that I have constructed a resistor-coupler unit which is very small and compact and one that is readily connected into a radio circuit.

100 What I desire to claim is:

105 1. A radio resistor coupler unit comprising, a casing having a window therein and 110

- adapted to receive a designation card, a pair of resistance units mounted within the casing and serving to hold the designation card in place in the window, terminal posts for each end of the resistance units extending through to the front of the casing, a condenser within the casing and electrically bridging the ends of both resistance units and a cover plate for the bottom of the casing.
2. A radio resistor coupler unit comprising, a casing of insulating material having a flange portion and a body portion extending above the flange portion, said body portion having a depressed window, a designation card adapted to show through said window, a pair of resistance units positioned within the body part of the casing and extending over the ends of the designation card, terminal posts for each end of the resistance unit extending through the body part of the casing, a condenser mounted across the ends of the two resistance units and a cover plate for the bottom of the casing fastened to the flange portion thereof.
3. A radio resistor coupler unit comprising, a casing of insulating material having a flange portion and a body portion extending above the flange portion, said body portion having a depressed window, a designation card positioned across said window, a pair of resistance units extending across the window behind the designation card and terminal posts for anchoring each end of said units and extending through to the front of the casing, a condenser within the casing and having a pair of arms acting as terminals and mounting lugs, said arms being anchored within the casing by one pair of said terminal posts and a cover plate for the bottom of the casing.
4. A radio resistor coupler unit comprising, a casing of moulded insulating material having a tapered body portion and projecting flanges from at least two sides at the base of said body portion, said body portion having a window therein, a designation card positioned across said window, a pair of resistance units extending across the window behind the card and terminal posts adjacent opposite corners of the window for anchoring each end of said units and ex- tending through to the front of the casing, a condenser mounted within the casing over said units by one pair of said terminal posts, a cover plate for the bottom of the casing and fastening means therefor extending through said flanges.
5. A radio resistor coupler unit comprising, a casing having a window therein and adapted to receive a designation card, a pair of resistance units mounted within the casing, back of said card and across said window, terminal posts extending through the casing adjacent the opposite corners of said window and serving to anchor said resistance units in place, a condenser within the casing adjacent said units and having a pair of arms fastened to the casing by one pair of said terminal posts and a cover plate over the bottom of the casing.
6. A radio resistor coupler unit comprising, a casing having a window therein and adapted to receive a designation card, a pair of resistance units mounted within the casing, terminal posts extending through the casing and anchoring said resistance units in place, a condenser within the casing adjacent said units and having a pair of arms fastened to the casing by one pair of said terminal posts and a cover plate over the bottom of the casing.
7. A radio resistor coupler unit comprising, a casing having a window therein and adapted to receive a designation card, a pair of resistance units mounted within the casing, terminal posts extending through the casing and anchoring said resistance units in place, a condenser within the casing adjacent said units and having a pair of leads fastened to one pair of said terminal posts.
8. A radio resistor coupler unit comprising, a casing having a window therein and adapted to receive a designation card, a pair of resistance units mounted within the casing, terminal posts on the casing and having connections to said resistance units, a condenser within the casing adjacent said units and having a pair of leads fastened to one pair of said terminal posts.

In testimony whereof, I affix my signature.

LEON S. BRACH.
